Attorney

Patented Mar. 10, 1925.

UNITED STATES PATENT OFFICE.

JERRY NOVAK, OF SOUTH MILWAUKEE, WISCONSIN.

KNEE REST.

Application filed July 5, 1923. Serial No. 649,654.

To all whom it may concern:

Be it known that I, JERRY NOVAK, a citizen of the United States of America, residing at South Milwaukee, in the county of Milwaukee and State of Wisconsin, have invented certain new and useful Improvements in Knee Rests, of which the following is a specification.

This invention relates to certain new and useful improvements in knee rests and particularly to the type employed by persons in painting or scrubbing of floors, the rest including a cushioned pad upon which a person kneels to relieve the knees of the usual strain during the performance of such duties.

A further object of the invention is to provide a knee rest especially designed for use by floor scrubbers wherein a forwardly positioned splash board is so designed for cooperation with the bottom board of the rest to cause water splashing on the front board to be drained at the lower end thereof upon either side without falling upon the bottom board of the rest.

With the above and other objects in view as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a perspective view of a knee rest constructed in accordance with the present invention showing the forward side wall of the frame structure of greater height than the end walls and being upwardly and forwardly curved to form a splash board,

Figure 2 is a top plan view of the rest,

Figure 3 is a fragmentary front elevational view,

Figure 4 is a detail sectional view taken on line IV-IV of Fig. 3 showing the longitudinally extending slots in the forward edge of the bottom board and at the base of the forward splash board, and

Figure 5 is a perspective view of another form of the invention.

Referring more in detail to the accompanying drawing, the knee rest embodies a bottom board 1, preferably rectangular in plan view mounted upon skids 2 suitably

positioned upon the lower face thereof to provide a proper support therefor.

The bottom wall board 1 carries perpendicular end walls 3 having hand opening grips 4, and a forwardly positioned splash board 5 with the rear side of the rest open to permit a person to kneel upon the bottom board 1. The splash board 5 is of greater height than the end wall 3 and is upwardly and forwardly curved as at 5^a as clearly shown in Figs. 1 and 4. The forward edge of the bottom board 1 is longitudinally slotted as at 6 at the lower edge of the splash board 5 as shown in Fig. 4. A knee rest in the form of a cushion includes a water-proof covering or bag 7 filled with cushioning material 8, the opposite end of the cushion being secured as at 9 to the bottom board 1 as clearly shown in Figs. 2 and 3.

In the use of the device, a person kneels upon the cushion pad 7 and leans forwardly of the splash board 5 for washing a floor surface or performing similar duties. During the washing of a floor, water will splash in different directions, and the elevated splash board 5 will materially reduce back splash of the water upon the knee pad 7 and also upon the person kneeling thereon. Should any water splash over the upper curved edge 5^a of the splash board, the same will drain downwardly upon the inner face thereof and fall through the slot 6 and return to the floor F without contacting the knee pad 7 or being thrown upon the person using the same.

Another form of the invention is shown in Fig. 5 wherein the bottom board 1^a supports a knee pad 7^a and has end walls 3^a and a forward splash board 5^d of equal height, this form of the invention eliminating the drain slot 6 illustrated in Fig. 4 and also the upper curved edge 5^a of the splash board.

While there are herein shown and described the preferred embodiments of the present invention, it is nevertheless to be understood that minor changes may be made therein without departing from the spirit and scope of the invention as claimed.

What is claimed as new is:—

A knee rest for use in floor scrubbing comprising a shallow tray having a bottom board, a front wall and end walls, said end walls being provided with hand holes and

projecting forwardly of the bottom wall, the front wall being secured to the end walls in spaced relation to the forward edge of the bottom to provide a slot extending along 5 said forward edge, said front wall further extending above the side walls and having its upper portion curved forwardly, thin skids at the corners of the bottom beneath

the same to hold the bottom raised and the slotted portion of the device clear of the 10 floor, and a pad on said bottom board spaced from the side edges thereof and spaced from the front wall to provide a channel communicating with the slot.

In testimony whereof I affix my signature.
JERRY NOVAK.
